UNITED STATES PATENT OFFICE.

FRED A. GARVIN, OF WASHINGTON, DISTRICT OF COLUMBIA.

STONE-RAKE.

1,223,268.

Specification of Letters Patent. Patented Apr. 17, 1917.

Application filed August 26, 1916. Serial No. 11",098.

To all whom it may concern:

Be it known that I, FRED A. GARVIN, a citizen of the United States, residing at Washington, District of Columbia, have invented certain new and useful Improvements in Stone-Rakes; and I do hereby declare the following to be a full, clear, and exact description of the invention, such as will enable others skilled in the art to which it applies to make and use the same.

This invention relates to new and useful improvements in a stone rake and one of its objects is the provision of a device of this character, which shall be simple, durable and efficient, and which may be manufactured and sold at a comparatively low cost.

Another object of this invention is to provide a frame mounted on a pair of wheels and having a plurality of plows thereon for digging up stones embedded in the surface of the ground.

A further object of this invention is to provide endless conveyers coöperating with the plows to receive the stones dug up and the ones collected from the surface of the ground for carrying them to a stone collecting receptacle located upon the frame, whereby stones may be readily collected and deposited at a desired place.

A still further object of this invention is to provide means for raising the plows from an engagement with the ground when the stone receptacle has been filled, so that the device may be rendered inoperative to prevent overloading of the receptacle.

With these and other objects in view as will become more apparent as the description proceeds, the invention consists in certain novel features of construction, combination and arrangement of parts as will be hereinafter more fully described and claimed.

For a complete understanding of my invention, reference is to be had to the following description and accompanying drawings, in which:

Figure 1 is a top plan view of a stone rake, constructed in accordance with my invention,

Fig. 2 is a longitudinal sectional view of the same,

Fig. 3 is a detail view partly in section of the stone collecting receptacle,

Fig. 4 is a detail elevation of the means for raising and lowering the plow, and 55
Fig. 5 is a detail sectional view taken on the line 5—5 of Fig. 1.

Referring in detail to the drawings, the numeral 1 indicates a substantially rectangular frame having secured adjacent the rear end thereof an axle 2 having each end reduced to form spindles 3 on which are journaled squared sleeves 4. The squared sleeves 4 have formed upon their inner ends gears 5 and also have secured thereon 65 ground wheels 6 for supporting the frame 1. The frame 1 is secured thereto vertical standards 7 to which are secured upwardly inclined handles 8 which have their lower forward ends secured to the frame. The 70 standards and handles are connected together by a transverse bar 9.

A conveyer supporting member consisting of a plurality of parallel extending bars 10 are secured together by a transverse strip 11 75 and the outer bars of the series are of greater width than the remaining bars to form a trough-like construction and each of the bars 10 is pivotally secured to bracket 12 carried by the axle 2. The forward ends of 80 the bars 10 are reduced and inclined downwardly to form plow points 13 which are connected together in V-shaped formation as clearly illustrated in Fig. 1. A transverse shaft 14 is journaled in the bars 10 adjacent 85 the plow points 13 and has mounted thereon gears 15 which rotatably support endless conveyers 16. The endless conveyers 16 are in turn mounted upon enlarged gears 17 carried by a drive shaft 18 which is journaled 90 within the frame 1 at a point rear of the axle 2 and has mounted on each end gears 19 that mesh with the gears 5 for rotating the conveyers 16, so that when stones are dug up by the plow points 13 they are caught 95 by the conveyer 16 and carried rearwardly.

A stone collecting receptacle 20 constructed from a plurality of interwoven wires is provided with supporting arms 21 on each end thereof for overlying a portion of the 100 rear end of the frame 1 adjacent the enlarged gears 17 so that the stones that are carried rearwardly by the conveyers may fall into the stone collecting receptacle 20. A rack 22 is secured to the frame 1 and has 105 pivoted thereto a lever 23 having the usual

hand grip 24 for operating the dog 25 which engages the teeth of the rack 22. An arm 26 is formed on the lever 23 and is pivotally secured to the forward end of the conveyer 5 supporting construction, whereby upon operating the lever 23, the plow points 13 may be caused to engage and disengage the ground.

In operation, draft animals are fixed to the forward end of the frame 1 in any suitable manner and by pushing the lever 23 forwardly, the plow points 13 will be lowered into an engagement with the ground. Upon forward movement of the device, the 15 plow points will dig into the ground and dig up any stones that may be embedded in the ground near the surface thereof, causing the stones to pass upwardly over the plow points on to the conveyers 16 thence they 20 travel rearwardly into the stone collecting receptacle 20. After the stone collecting receptacle 20 has been filled, the lever 23 may be drawn rearwardly raising the plow points from an engagement with the ground thus 25 rendering the device inoperative to prevent overloading of the stone collecting receptacle. The device then may be driven to a convenient place and the stone collecting receptacle 20 removed from the frame and 30 emptied. If not desiring to pull the device to a desired place, the stone collecting receptacle 20 may be removed from the frame

and emptied into a wagon or cart which may be brought adjacent thereto for carrying away the stones to a given point. 35

While I have shown and described the preferred embodiment of my invention, it will be understood that minor changes in construction, combination and arrangement of parts may be made without departing 40 from the spirit and scope of the invention as claimed.

Having thus described my invention, what I claim is:—

A stone rake comprising a frame, an axle 45 secured to said frame, wheels carried by said axle, a conveyer rack pivoted to said axle and consisting of a plurality of parallel bars having their forward ends reduced and connected together in V-shaped formation to form plow points, a transverse strip connecting said bars together, an endless conveyer mounted on said rack for receiving stones from the plow points, and a stone collecting receptacle carried by the rear end of the frame to receive the stones from the conveyers. 50

In testimony whereof I affix my signature in presence of two witnesses.

FRED A. GARVIN.
